UNITED STATES PATENT OFFICE.

PERCY H. THOMAS, OF EAST ORANGE, NEW JERSEY, ASSIGNOR TO COOPER HEWITT ELECTRIC COMPANY, OF NEW YORK, N. Y., A CORPORATION OF NEW YORK.

ELECTRIC SWITCH.

1,012,753.

Specification of Letters Patent.

Patented Dec. 26, 1911.

Application filed February 10, 1904. Serial No. 192,924.

To all whom it may concern:

Be it known that I, PERCY H. THOMAS, a citizen of the United States, and resident of East Orange, county of Essex, State of New Jersey, have invented certain new and useful Improvements in Electric Switches, of which the following is a specification.

It is found to be convenient in many kinds of electric work to employ a mercury switch in which a container of insulating material is supplied with electrodes capable of being connected with an external circuit and in which, in the closed position of the switch, a mass of mercury bridges the space between the electrodes. The act of rotating the container through a certain distance is sufficient to remove the electrodes away from the mercury and break the circuit.

The present invention relates to a switch of this character. In operating such switches it is important that the external circuit should not be interrupted, and to this end I provide flexible or sliding connections which maintain the continuity of the outside circuit, as will be explained hereinafter. Should it be desired to cause a rupture of the circuit through the medium of the switch by a quick movement, the flexible connection may be itself made of elastic material and may be put under tension when the switch is closed and simply released when it is desired to open the switch. Under such circumstances, the elastic material forming the flexible connection will act to cause a quick rupture of the circuit by rotating the container rapidly through a sufficient arc to cause a quick separation of the electrodes or terminals and the mercury.

In the accompanying drawings I have shown several forms or types of the apparatus named herein.

For example, Figure 1 is an end elevation of a switch embodying the idea of a flexible connection as described; Fig. 2 is a side elevation of a similar device in which, however, the flexible elements are elastic.

Referring to the first figure of the drawings, 1 is a container which may be of glass or other good insulating material. The said container is provided with depressions or receptacles, one of which is shown at 2, in Fig. 1, and both of which appear in Fig. 2, being designated by the characters 2, 2. In the bottom of the depressions or receptacles 2, 2 are pieces, 3, 3, of platinum,

which are connected by wires or bars, 4, 4, with rings, 5, 5, on the ends of the container 1.

The container, as shown more clearly in Fig. 2, is narrowed at its ends and provided with necks or extensions, 6, 6, which are supported in openings in the posts, 7, 7, and adapted to be rotated therein.

To the rings 5, 5 are connected the ends of flexible connections, 8^a, 8^a, the same being joined together by suitable clips, shown at 9, 9.

At 10, 10 are shown the binding posts or connections of the external circuit. The flexible conducting elements 8^a, 8^a are connected to the said binding posts and when the switch is in its closed position and the parts are connected up as indicated above, there is a complete circuit from one binding post to the other by way of the flexible element, 8^a, ring 5, wire or bar 4, contact plate 3, and the mercury on one side, back to the other binding post through a similar set of elements in the reverse order.

To move the switch, the container 1 may be surrounded by a strap, or band, 11, and from the said strap may project a handle, 12, by means of which the position of the container may be regulated or controlled. Should the flexible parts 8^a be made of elastic material, such as is intended to be illustrated in Fig. 2, the handle 12 may, in order to close the switch, be pushed down into a horizontal position. In order to hold the switch in closed position a catch or detent, 13, is shown with a handle, 14, the said catch or detent being pivoted at 15 so as to have a considerable range of movement. When it is desired to open the switch, the handle may be pushed away from engagement with the arm 12, whereupon the power of the spring 8^a will throw the switch open by a quick movement.

It will be understood that any other means for securing the quick rupture of the circuit may be employed instead of those illustrated in Fig. 2.

In the type of switch heretofore described, it is assumed that current is passed through the circuit-breaker by way of a mercury path.

I claim as my invention:—

1. A circuit breaker comprising an insulating container, internal electrodes therefor and a conducting liquid therein for con-

necting said terminals in the inclosed position in combination with trunnions for mounting said circuit breaker and bearings for said trunnions, together with flexible 5 spiral conductors curved about the axles of the trunnions and making connection with a suitable electric circuit.

2. An electric switch comprising an insulating container rotatably mounted, circuit 10 terminals within the container and a mercury bridge between the said terminals when the switch is in its closed position, in combination with spring connections between the said circuit terminals and the external circuit, and a lever for holding the switch in 15 the closed position, the spring being then under tension.

3. An electric switch comprising an insulating container, circuit terminals within the 20 container, and a conducting liquid bridging the said terminals when the switch is in its closed position, the said container being provided with trunnions, journals in which the trunnions are mounted, in combination with 25 conducting pieces mounted on said trunnions, connections from each conducting piece to one of the said circuit terminals, and other connections from the said conducting pieces to the external circuit, such connections being of flexible elastic material whereby 30 a partial rotation of the container is permitted and whereby the switch may be restored to closed position when the container is released.

35 4. An electric switch comprising an insulating container rotatably mounted, circuit terminals within the container and a mercury bridge between the said terminals when the switch is in its closed position, in combination 40 with spring connections between the said circuit terminals and the external circuit, and a lever for holding the switch in the closed position.

45 5. An electric switch comprising an insulating container, rotatably mounted, circuit terminals within the container, a mercury bridge extending between the said terminals when the switch is in its closed position, continuously maintained spring connections between 50 the said terminals and the external circuit while the switch is in operation,

a lever for holding the switch in closed position, and means for releasing the switch for rupturing the switch circuit.

6. A circuit breaker comprising an insulating container, internal electrodes therefor and a conducting liquid therein for connecting said terminals in the inclosed position in combination with trunnions for mounting said circuit breaker and bearings for 60 said trunnions, together with elastic spring conductors curved about the axles of the trunnions and making connection with a suitable electric circuit.

7. The combination of an electric circuit 65 breaker comprising an insulating container so formed as to provide trunnions for permitting rotation of said circuit breaker and containing internal electrodes and a conducting liquid for connecting and disconnecting 70 the same and bearings for said trunnions, with flexible leads connecting said insulating container with an external circuit, said flexible leads being adapted to move in a plane at right angles to the axis of rotation, 75 together with terminals for said flexible conductors attached to the insulating container and connected with the said inside terminals.

8. The combination of an electric circuit breaker comprising an insulating container 80 so formed as to provide trunnions for permitting rotation of said circuit breaker and containing internal electrodes and a conducting liquid for connecting and disconnecting the same, and bearings for said 85 trunnions, with flexible leads connecting said insulating container with an external circuit, said flexible leads being adapted to move in a plane at right angles to the axis 90 of rotation and attached to the circuit breaker in the immediate neighborhood of the said trunnions, together with terminals for said flexible conductors attached to the insulating container and connected with the said inside terminals.

95 Signed at New York, in the county of New York, and State of New York, this 6th day of February, A. D. 1904.

PERCY H. THOMAS.
